UNITED STATES PATENT OFFICE.

JOHN E. MOORE, OF RENO, NEVADA.

CURTAIN SUPPORT.

Application filed April 18, 1927. Serial No. 184,769.

This invention relates to brackets adapted for supporting rod members.

An object of the invention comprehends means for securing the bracket in position 5 for use devoid of fastening devices which ordinarily mar and detract from the finish of the wood work or other trim.

Another object of the invention contemplates supporting members upon which may 10 be carried a multiplicity of rod members.

With the above and other objects in view, the invention further consists in the following novel features and details of construction 15 to be hereinafter more fully described, illustrated in the accompanying drawing and pointed out in the appended claim.

In the drawing:—

Figure 1 is a fragmentary elevation of a 20 frame structure illustrating the application of the invention.

Figure 2 is a top plan view of the frame structure and invention.

Figure 3 is a vertical sectional view taken 25 through a portion of the frame structure and illustrating the anchoring means for the brackets.

Figure 4 is a perspective of the bracket per se.

Referring to the drawing in detail, where- 30 in like characters of reference denote corresponding parts, the reference character 10 indicates a frame either for a door or window.

The invention is designed for application upon the upper ledge of the frame and in carrying out the invention I provide substantially inverted L-shaped members 11 which terminate to provide pointed end portions 12. Said members are outwardly offset as at 12' to provide inwardly and laterally disposed portions 13 which are subsequently bent upon themselves and retracted along the lines of the initial formation and laterally offset at right angles to the members 11 to provide shoulder portions 14 adapted for engagement with the outer sides of the frame substantially as illustrated in Figure 2 of the drawing. The extremities 14' of the shoulder portions are extended forwardly and inwardly as at 14" to provide laterally disposed portions 15; both of which being arranged in parallelism with the portions 13.

Various types of single rods formed of telescopically associated sections may receive the portions 13 and 15 within the ends thereof. In the application of the invention the curtains and draperies are hung upon the

rods. The portions 13 and 15 of the brackets are then inserted within the ends of the rods. The length of the rods is then regulated and the entire structure is elevated to the height 60 of the upper ledge of the frame and the pointed end portions 12 struck with smart blows to embed the same within the aforementioned ledge. The vertical portions of the substantially inverted L-shaped members 65 will cooperate with the shoulder portions 14 to sustain the portions 13 and 15 in horizontal planes and to support draperies and curtains of different weights.

The invention is designed for application 70 upon the various forms of window frames and which due to its construction obviates the employment of the customary fastening elements and brackets which are screwed to the faces of the frame structures. Such fastening devices are usually left upon the frames when the brackets and rods are removed and which detracts from the finish of the particular frame structure.

The invention is susceptible of various 80 changes in its form, proportions and minor details of construction and the right is herein reserved to make such changes as properly fall within the scope of the appended claim.

Having thus described the invention, what 85 is claimed is:—

A bracket formed of wire having a substantially inverted L-shaped attaching portion upon one end terminating to provide a pointed end, an outwardly offset portion 90 formed upon the lowermost end of the attaching portion, laterally disposed portions formed upon the outermost ends of the outwardly offset portions and at right angles thereto, the latter mentioned portions being 95 bent upon themselves and retracted along the adjacent surface thereof and the outwardly offset portion, a shoulder laterally disposed upon the retracted portion in oppositely disposed relation to the laterally disposed portion and at right angles to the depending portion of the attaching portion, the extremity of the shoulder being forwardly disposed in spaced parallelism to that of the outwardly offset portion and subsequently offset in parallelism to that of the laterally disposed portion, and the offset of the extremity being bent upon itself after the manner of the retracted portions for the initial laterally disposed portions.

In testimony whereof I affix my signature.
JOHN E. MOORE.
